UNITED STATES PATENT OFFICE.

CARL L. RHOTEN, OF ARRIBA, COLORADO.

GRAIN-ELEVATING CONVEYER.

Application filed September 8, 1925. Serial No. 55,146.

To all whom it may concern:

Be it known that I, CARL L. RHOTEN, a citizen of the United States, residing at Arriba, in the county of Lincoln and State of Colorado, have invented certain new and useful Improvements in Grain-Elevating Conveyers, of which the following is a specification.

This invention relates to grain elevating conveyers, and has more particular reference to an improved means for automatically cutting off the flow of grain to the conveyer when the latter is rendered inoperative and for automatically permitting the flow of grain to the elevator when the same is placed into operation.

A further object of the invention is to provide a grain feed controlling device for grain elevating conveyers wherein the amount of grain allowed to flow to the conveyer is automatically regulated in proportion to the speed of operation of the conveyer so that the feeding of an excessive amount of grain to the conveyer is prevented.

Still another object of the invention is to provide a grain feed controlling device of the above kind which is extremely simple and durable in construction as well as efficient in operation.

Other objects will appear as the nature of the invention is better understood, and the same consists in the novel form, combination and arrangement of parts, hereinafter more fully described, shown in the accompanying drawings and claimed.

In the drawings, wherein like reference characters indicate corresponding parts throughout the several views,

Figure 1 is a fragmentary view partly in side elevation and partly in vertical section, of a grain elevating conveyer equipped with a grain feed controlling device constructed in accordance with the present invention,

Figure 2 is a fragmentary vertical section taken substantially upon line 2-2 of Figure 1,

Figure 3 is a horizontal sectional view taken substantially upon line 3-3 of Figure 1, and

Figure 4 is an enlarged fragmentary detail view with parts broken away and in section, and illustrating details of the grain feed controlling device.

Referring more in detail to the drawings, a grain elevating conveyer is herein shown embodying a casing composed of a pair of

vertical legs 5 and 6 which communicate at their lower ends with opposite sides of a boot 7. Movable in this casing is an endless conveyer member herein shown as embodying a pair of endless chains 8 which are suitably driven and which pass around sprockets 9 secured upon a foot shaft 10 journaled transversely of the boot portion 7 of the elevator casing. The chains 8 are connected at intervals by means of buckets 11 which complete the endless movable member of the conveyer, and the chains are caused to travel so that the buckets move downwardly in the leg 5 of the casing so as to dip into the grain 70 in the boot 7 and then carry the same upwardly in the leg 6.

In accordance with the present invention, horizontal superimposed spaced brackets 12 extend between and rigidly connect the legs 5 and 6, and a hollow vertical shaft 13 is journaled in bearings 14 carried by these brackets. The upper bearing forms part of a thrust bearing, the other part 15 of which is secured on the upper end of the hollow shaft 13 and forms the hub of a horizontal fly wheel 16. In this way the weight of the fly wheel is effectively supported.

Suitably supported in a horizontal position by means of a shaft hanger 17 carried by the brackets 12 is a transverse shaft 18 (see Figure 2) and secured upon the inner end of this shaft 18 is a beveled gear 19 which meshes with a beveled gear 20 fixed upon the intermediate portion of the hollow shaft 13. A pulley 21 is fixed upon the outer end of the shaft 13 and this pulley is operatively connected by means of an endless driving belt 22 with the pulley 23 fixed upon a projecting end of the conveyer foot shaft 10. It is thus apparent that when the endless member of the conveyer is driven, rotation of shaft 10 will be imparted to the hollow vertical shaft 13 and consequently to the fly wheel 16 for a purpose which will presently become apparent.

Pivottally mounted as at 24 upon the margin of the fly-wheel 16 are a pair of opposed bell crank levers 25, the axes of which are parallel and horizontal so that said bell crank levers swing vertically. The lower arms of the bell crank levers 25 engage the under side of a disc 26 which is fixed upon the upper end of a shaft 27 slidably movable in the hollow shaft 13, and the upper arms of the bell crank levers 25 are weighted at

their free ends as at 28 whereby the disc 26 and shaft 27 are normally allowed to lower by gravity.

The lower end of the shaft 27 has a grooved ring or a pair of collars 29 fixed thereto between which collars or flanges of the grooved ring is journaled a ring 30 rigid with the inner end of a horizontal arm 31 which is rigid with the intermediate portion 10 of a horizontal rod 32. The rod 32 lies at one side of the conveyer and the arm 31 projects laterally from one side thereof transversely of the conveyer so as to connect with the shaft 27 as described, and rigid with 15 the ends of the rod 32 are further horizontal arms 33. Opening into the boot 7 at the lower ends of the legs 5 and 6 are inclined chutes 34 which extend from the usual bins, not shown, into which the grain is dumped 20 for being fed to the elevator. The grain falls into the boot 7 from the bins through the chutes 34 by gravity in a well known manner, and the flow of the grain to the boot is controlled by means of vertically slideable 25 gate valves 35. Each end arm 33 of the rod 32 is connected to the upper end of one of the gate valves 34 by means of a link 36 which is of such length as to permit the gate valves 35 to completely close the chutes when 30 the shaft 27 is in its normal lowered position.

In operation, when the conveyer is rendered operative the shaft 10 rotates and communication of the rotation thereof to the hollow shaft 13 is effected through the gearing hereinbefore described. Upon rotation of the shaft 13 the fly wheel 16 is caused to turn and the weighted bell crank levers 25 swing under the action of centrifugal force 40 so as to cause the shaft 27 to move upwardly by engagement with the disc 26. The upward movement of the shaft 27 is transmitted to the rod 32 so that an upward pull is simultaneously exerted upon the gates 35 and the grain thereby allowed to flow into the boot 7. The opening movement of the gates 35 will be proportional to the speed 45 of travel of the endless member of the conveyer so that the proper amount of grain fed into the boot is insured. In other words, the faster the conveyer travels, the greater the carrying or conveying capacity of the same, and a corresponding increase in the feed of grain through the boot is had. By 50 preventing excessive flow of grain to the elevator its most efficient operation is insured without loss of power.

When the conveyer is rendered inoperative the shaft 27 will automatically lower so as to permit the gate valves 35 to completely close the chutes 34 and completely cut off the flow of grain to the boot. When this is

done the grain dumped into the bins will be prevented from flowing into the boot 7 and clogging the conveyer.

Minor changes may be made without departing from the spirit and scope of the invention as claimed.

What I claim as new is:

1. In combination, a grain elevating conveyer including a casing having a boot and embodying a transverse driven foot shaft journaled in the boot, an endless conveyer member movable in the casing and operatively associated with said foot shaft, and a governor operated means operatively connected to said foot shaft for controlling flow of grain into said boot, said controlling means including dump bin chutes discharging into the boot and provided with controlling gate valves, and a slideable governor operated vertical rod connected to said valves, the connection between said vertical rod and said valves embodying a horizontal rod having rigid lateral arms respectively connected to said vertical rod and said valves. 70 75 80 85

2. In combination, a grain elevating conveyer including a casing having a boot and a pair of vertical legs, an endless conveyer member movable in said casing, a foot shaft journaled in the boot and operatively associated with said endless conveyer member, a vertical hollow shaft journaled between the casing legs and having a fly wheel secured thereon, operative connections between said foot shaft and said hollow vertical shaft, chutes arranged to discharge into said boot, gate valves for controlling the flow of grain through the chutes, and speed responsive means associated with the fly wheel for operating said valves and including a shaft slideable in said hollow shaft. 90 95 100

3. In combination, a grain elevating conveyer including a casing having a boot and a pair of vertical legs, an endless conveyer member movable in said casing, a foot shaft journaled in the boot and operatively associated with said endless conveyer member, a vertical hollow shaft journaled between the casing legs and having a fly wheel secured thereon, operative connections between said foot shaft and said hollow vertical shaft, chutes arranged to discharge into said boot, gate valves for controlling the flow of grain through the chutes, and speed responsive means associated with the fly wheel for operating said valves and including a shaft slideable in said hollow shaft, and weighted levers pivoted on the fly wheel, said slideable shaft having a disk secured on its upper end engaged by said levers. 105 110 115 120

In testimony whereof I affix my signature.

CARL L. RHOSEN
